SCAVENGING THE CYLINDERS OF DOUBLE-BORE CYLINDER COMBUSTION ENGINES

August Portmann, Winterthur, Switzerland, assignor to the firm Schweizerische Lokomotiv- und Maschinenfabrik, Winterthur, Switzerland

Application August 16, 1937, Serial No. 159,412
In Germany August 17, 1936

3 Claims. (Cl. 123—53)

This invention relates to the scavenging of the cylinders of double-bore-cylinder internal combustion engines, the two bores of each cylinder of which being interconnected at the ends thereof adjoining the cylinder head by a communication channel and the scavenging air entering one of the cylinder bores at the lower end of the piston swept surface thereof and discharging at the lower end of the piston swept bore surface of the other cylinder. In double-bore-cylinders of this kind, the communication channel must be kept down to small dimensions with a view of obtaining an adequately high compression pressure, in consequence of which, the narrow cross section provided for this channel, in conjunction with the requirement of diverting the flow of scavenging air therethrough, causes local accumulations of inert gases particularly in the exhaust cylinder, during the scavenging operation.

According to this invention these difficulties are met by giving the cross section of the intermediary passage a substantially oval shape.

In the accompanying drawings several constructional forms of double-bore-cylinders are illustratively exemplified for explaining the apparatus according to the invention as this is applied to these cylinders. In these drawings:

Fig. 1 is a vertical sectional view on the line I—I of Fig. 3 of a double-bore-cylinder of a first constructional form in which the scavenging air is imparted a twist at its entry into the admission cylinder bore;

Fig. 2 is a sectional view on the line II—II in Fig. 1;

Fig. 3 is a sectional view on the line III—III in Fig. 1;

Fig. 4 is a sectional view of a detail on the line IV—IV in Fig. 3;

Fig. 5 is a sectional view similar to Fig. 1 of a double-bore-cylinder of a second constructional form in which the scavenging air is imparted a twist in the exhaust cylinder bore;

Fig. 6 is a sectional view on the line VI—VI in Fig. 5;

Fig. 7 is a sectional view of a modified detail of Fig. 6;

Fig. 8 is a sectional view, similar to Fig. 5, of a double-bore-cylinder of a third constructional form in which the communication channel is provided with an insert;

Fig. 9 is a sectional view on the line IX—IX in Fig. 8, as seen in the direction of the arrows shown;

Fig. 10 is a sectional view on the line X—X in Fig. 8;

Fig. 11 is a schematic sectional view illustrating the path of the helical flow of scavenging air as diverted by the communication channel.

Fig. 12 shows the assembled engine.

In all figures of the drawings, the pistons a_1 ,

a_2 cooperate with a pair of cylinders b connected by a common combustion chamber, the cylinders being cooled by means of a cooling water jacket h . The manner in which the pistons a_1, a_2 , that is, the piston rods b_1, b_2 are operatively connected with the crankshaft, is not shown as this is a matter known per se. The two cylinder bores intercommunicate through the communication or intermediary channel or passage i . The scavenging air enters the admission cylinder bore c_1 through slots o_1 , which are opened by the admission piston a_1 when the latter is in the vicinity of the lower dead center thereof, and discharges from the exhaust cylinder bore c_2 through slots o_2 .

As is evident from Fig. 3, the scavenging air entering the entrance in the direction of the arrow to the left in Fig. 1 is given a twisted or helical direction by the provision of the ribs p between the individual slots o_1 , said ribs being constructed as guide vanes inclined to the radial direction as indicated by the arrow R . In order to obtain a uniform distribution of scavenging air over the entire cylinder bore circumference, special guide vanes q of greater length are provided which have the effect that the entrance slots situated in the space q_1 are also supplied with an adequate amount of scavenging air entering in the required direction. Alternatively, several vanes q may be distributed over the circumference of the entrance. The disposition of the vanes p depends upon the twist or whirling movement to be imparted to the scavenging air. When it is desired to maintain the whirling movement only in the entrance cylinder bore, it suffices to impart to the flow of scavenging air less twist than if the whirling movement is to be maintained in the exhaust cylinder bore also.

When it is desired to obtain a whirling movement in the exhaust cylinder bore also, this can be effected in the manner mentioned above by producing in the admission cylinder bore a whirling movement of such high intensity that this movement is maintained by diversion in the communication channel i , as shown in Fig. 11. In this case, the intensity of whirling movement is, advantageously, so chosen that in the exhaust cylinder bore also during the scavenging period at least one turn of inherent rotational movement is carried out. The special form of communication channel as shown in Figs. 1 and 2 is particularly well suited for maintaining a continuous helical flow, which form results in a very effective scavenging operation with any kind of scavenging irrespective of whether an inherent rotational movement is set up in the helical flow or not.

Alternatively, the formation of a whirl in the exhaust cylinder bore can be effected, as shown in Fig. 6, by disposing the axis of the communi-

cation channel i so that it is not in the joining line of the two cylinder bore centres z_1, z_2 as is evident, for example, from Fig. 9, but so as to lead into the exhaust cylinder bore in a somewhat tangential direction. By this means a whirl is obtained in the exhaust cylinder bore even when in the admission cylinder no whirl was produced. To the same end, the communication channel may be constructed as shown in Fig. 7, 10 the whirls setting up in the two cylinder bores then having the same direction of rotational movement inherent thereto in all cases where at the same time in the admission cylinder bore a whirl is produced. By means of the arrangement 15 shown in Fig. 6 the whirls in the admission as well as in the exhaust cylinder bore have inherent thereto rotational movements of different directions.

The transfer of a whirl set up in the admission 20 cylinder bore into the exhaust cylinder bore is facilitated by giving the communication channel i a substantially oval shape, as shown in Figs. 2 and 10, due to the fact that this cross sectional shape highly contributes to maintaining the 25 whirling movement, as tests have shown. Advantageously, the intensity of the whirling movement is so chosen that this movement is maintained even during the ignition and combustion periods, so that in injecting the fuel in the tangential direction, as indicated by the arrow w in Fig. 2, the fuel is excellently admixed in the direction of the corresponding arrow and burnt.

By giving the admission piston a_1 a shape as shown in Figs. 1 and 8 the guidance of the whirl 30 is improved in that the chamfering a_3 forms together with the adjacent cylinder wall a circumferential groove. The chamfering along the line a_3 has the further advantage that the combustion space is given a somewhat concave shape 35 while at the same time the piston end face is convexed by the guide surfaces thus formed, so that the entry of the scavenging air into the channel i is facilitated in that, in this way, an eased off corner is formed at d_1 , which prevents the accumulation of inert non-scavenged gases. 40 In this case, the exhaust piston head can be made flat-ended as shown in the Figs. 1 and 8, without any detrimental effect, as regards the combustion space, so that the heat transmission to 45 the exhaust piston which is subjected to higher temperatures is facilitated.

With a view of obtaining a satisfactory scavenging of the entire space above the exhaust piston a_2 when the helical flow leaves the exhaust 50 cylinder bore c_2 in the direction of the arrow to the right in Fig. 1, the exhaust slots remote from the admission cylinder bore are shortened as, at r , in Fig. 4. This shortening may be provided, for example, for three slots o_3 , as indicated in Fig. 3. By this means the discharging scavenging air is compelled not merely to follow the shortest path away from the connecting channel i to the 55 exhaust space, but rather to discharge with a uniform distribution over the whole circumference of the exhaust cylinder and thus to sweep all portions of the interior of the exhaust cylinder bore for scavenging the same.

The cylinder may be cooled by means of air instead of water in which case the cooling water jacket h is dispensed with and instead the cylinder 60 b is provided with cooling ribs t (Fig. 12).

Various changes and modifications may be made in my invention without departing from its principle, by simply applying customary prac-

tice and established knowledge of the art to the present disclosure.

What I claim is:

1. In a combustion chamber connecting a pair of internal combustion engine cylinders successively scavenged by a vortex of air, means forming a combustion space extending substantially in a line joining the centers of the bores of said two cylinders at the upper end of the piston swept surfaces of said bores and provided with a cross section lying in a plane extending transversely of said joining line centrally between said bore centers in parallelism with said bores, and having an oblong-shape with rounded out corners, the longitudinal axis of the oblong being directed substantially perpendicularly to said bores, for reducing the height of said combustion space and guiding the rotating masses of said vortex circumferentially of said cross-section. 5

2. In an internal combustion engine having a pair of cylinders connected by a common combustion chamber and successively scavenged by a vortex of air, means forming in the preceding cylinder bore at the lower end of the piston swept surface thereof an air entrance having radially directed distributing surfaces of various sizes for uniformly distributing said vortex over the circumference of said bore, and means forming a combustion space extending substantially in a line joining the centers of the bores of said two cylinders at the upper end of the piston swept surfaces of said bores and provided with a cross-section lying in a plane extending transversely of said joining line centrally between said bore centers in parallelism with said bores, and having an oblong shape with rounded out corners, the longitudinal axis of the oblong being directed substantially perpendicularly to said bores, for reducing the height of said combustion space and guiding the rotating masses of said vortex circumferentially of said cross-section. 20

3. In an internal combustion engine having a pair of cylinders connected by a common combustion chamber and successively scavenged by a vortex of air, means forming a combustion space 25

extending substantially in a line joining the centers of the bores of said two cylinders at the upper end of the piston swept surfaces of said bores and provided with a cross-section lying in a plane extending transversely of said joining line centrally between said bore centers in parallelism with said bores, and having an oblong shape with rounded corners, the longitudinal axis of the oblong being directed substantially perpendicularly to said bores, for reducing the height of said combustion space and guiding the rotating masses of said vortex circumferentially of said cross-section into the succeeding cylinder bore, and means forming in said succeeding cylinder bore at the lower end of the piston swept surface thereof an exhaust opening, means forming exhaust passages, gas guide surfaces situated in said opening in advance of the outlet thereof and arranged circumferentially of said succeeding cylinder bore, a plurality of said exhaust passages being located in said outlet remote from the preceding cylinder bore and being arranged substantially flush at the top with other exhaust passages, the other exhaust passages being of greater vertical extent than said plurality of exhaust passages 30 for uniformly distributing the discharge of gas around the circumference of said succeeding cylinder bore. 35

AUGUST PORTMANN.
